DESIGN FOR A HAT

Samuel Scheuer, New York, N. Y.

Application January 14, 1936, Serial No. 60,573

Term of patent 3½ years

To all whom it may concern:

Be it known that I, Samuel Scheuer, a citizen of the United States of America, residing in the city of New York, county of New York, and State of New York, have invented a new, original, and ornamental Design for a Hat, of which the following is a specification, reference being had to the accompanying drawing, forming part thereof, Figure 1 is a perspective view of a hat showing my new design. Figure 2 is a side elevational view of a hat as shown in Fig. 1.

The hat of my design is characterized by the stitched double folds on the crown in combination with a stitched brim.

I claim:

The ornamental design for a hat substantially as shown and described.

SAMUEL SCHEUER.
